UNITED STATES PATENT OFFICE.

SAM WOLF, OF CHICAGO, ILLINOIS, ASSIGNOR TO JACQUES ROUSSO, OF LOS ANGELES, CALIFORNIA.

COUNTING DEVICE.

Application filed January 18, 1919, Serial No. 271,806. Renewed March 10, 1922. Serial No. 542,782.

To all whom it may concern:

Be it known that I, SAM WOLF, a citizen of the United States, and a resident of the city of Chicago, county of Cook, and State 5 of Illinois, have invented certain new and useful Improvements in Counting Devices, of which the following is a specification.

My invention relates to improvements in counting devices especially adapted for use 10 in conjunction with devices for counting perforated articles, such as grometed towels, and has for its object the provision of an improved construction of this character whereby articles having different sizes of 15 perforations or gromets therein may be readily and accurately counted.

Other objects will appear hereinafter.

The invention consists in the combinations and arrangements of parts herein- 20 after described and claimed.

The invention will be best understood by reference to the accompanying drawings forming a part of this specification, and in which,

25 Fig. 1, is a side view, shown partially in section, of a counting device embodying the invention,

Fig. 2, a partial top plan view illustrating the use of the same in conjunction with a 30 towel having a large gromet, and,

Fig. 3, a similar view, illustrating the use of the same in conjunction with a towel having a small gromet.

The preferred form of construction, as 35 illustrated in the drawings, comprises an upstanding hollow post 4, having a depressible spring-held plunger 5 therein, leading into a casing 6 containing suitable counting or registering mechanism which may be of 40 any usual or desired form. Such an arrangement of registering mechanism is illustrated and described in the co-pending application, Serial No. 270,876, filed January 13, 1919, by Jacques Rousso, assignee of 45 this application. A counting finger 6 is pivotally mounted at 7 in the upper end of post 4 and projects laterally through a slot 6' therein, said finger 6 being also pivotally connected at 8 to the upper end of the 50 plunger 5. A guide spring 9 is arranged in the side of post 4 opposite the slot 6', said guide spring projecting laterally through a slot 10 provided for the purpose. The spring 9 is in substantially wide or flattened 55 V form with the apex of the V positioned

opposite the extreme point of the finger 6 when the latter is in inwardly folded position. The device is especially adapted for use in counting grometed towels, a portion of such a towel being illustrated in Figs. 2 and 3, 60 wherein the towel 11 is provided with a gromet 12. It has been found that these gromets vary somewhat in size after considerable wear, and also that it is desirable to be able to count towels having gromets 65 which originally varied somewhat in size. The device illustrated is adapted to count such towels. In use, the towel is pressed downwardly over the post 4, the gromet therein forcing the finger 6 inwardly, flush 70 with the side of said post, which actuates the registering mechanism in casing 6, as will be readily understood. Where the opening in the gromet is larger than the diameter of the post 4, the finger 6 will not 75 be forced completely into the slot 6' and thus may fail to operate the registering mechanism. To prevent this, the spring 9 is provided, said spring having a resistance greater than the resistance of finger 6. 80 Thus where a towel is provided with a gromet which is considerably larger than the post 4, as illustrated in Fig. 2, the spring 9 will force the gromet to travel with its opposite side in close contact with the post 85 4, thus fully depressing the finger 6, whereupon the spring 9 will also yield somewhat to permit of the downward passage of the gromet in case the gromet is small enough to require such yielding. Thus the towels 90 or other articles having gromets of variable sizes may be readily and accurately counted.

While I have illustrated and described the preferred form of construction for carrying my invention into effect, this is capable 95 of variation and modification without departing from the spirit of the invention. I, therefore, do not wish to be limited to the precise details of construction set forth, but desire to avail myself of such variations 100 and modifications as come within the scope of the appended claims.

Having described my invention, what I claim as new and desire to secure by Letters Patent is:—

105

1. A device of the class described comprising a guide; a yieldable finger projecting from one side of said guide; and a yieldable guide projecting from the opposite side of said first mentioned guide, said yieldable 110

guide co-operating with said finger to compel complete operation of the latter upon the passage of articles of varying sizes over said first mentioned guide, substantially as described.

2. A device of the class described comprising a hollow post; a yieldable finger pivoted in said post, there being a slot in the side of said post through which said

10 finger projects; and a yieldable spring guide projecting from the opposite side of said post, said spring guide having a resistance greater than the resistance of said finger, substantially as described.

15 3. A device of the class described comprising a guide; a yieldable finger project-

ing from one side of said guide; and a yieldable guide projecting from the side of said first mentioned guide opposite said finger and co-operating therewith to cause operation of the latter by the passage of articles of varying sizes over said first mentioned guide, the resistance of said yieldable guide being greater than that of said finger, substantially as described. 20

25 In testimony whereof I have signed my name to this specification in the presence of two subscribing witnesses.

SAM WOLF.
